UNITED STATES PATENT OFFICE.

JOEL B. WOLFE, OF FRUITLAND, WASHINGTON.

STRINGED-INSTRUMENT PLAYER.

Application filed November 27, 1925. Serial No. 71,768.

This invention relates to improvements in devices for playing stringed instruments with the feet thereby leaving the hands free to manipulate and permit the performer to operate other instruments in addition to the one being played with the feet.

It is more particularly the object of this invention to provide a device whereby any form of stringed instrument having a sounding box from which a neck projects and along which the strings extend, may be played, this type of instrument being played by "stopping" the strings along the neck and "picking" or "plucking" the strings abreast of the sounding box, a typical instrument of this type being a banjo.

It is an object of this invention to provide a device as above outlined whereby instruments of this type can be anchored to the device and played without special provision being made, and whereby various sized instruments may be interchangeably fitted to the device.

The device of my invention includes a self-stable frame provided with means for securing an instrument therein and which is provided with pedal operated pressing or stopping mechanism for pressing or stopping the strings along the neck of the instrument, and, in the most improved form of the invention, this mechanism is slidably disposed in a manner to readily operate upon different longitudinally disposed portions of the neck.

My invention also includes novel picker mechanism which is pedal operated and in which the pickers are actuated to closely simulate the action of the human hand in picking the strings, to the extent that the pickers first engage, then tension, and finally quickly release the string for sounding vibration.

It is a feature of my invention to provide a novel form of damper adapted to be actuated by the knee of the player and acting upon the parchment preferably in the rear of the bridge, with respect to the neck end of the instrument.

My invention also includes a group of pedals for operating the stoppers, the pedals having a novel arrangement and construction whereby the ball of the foot may readily be shifted from one pedal to the other and whereby actuation of one pedal can be effected without interference with or accidentally operating another pedal.

It is a further feature to arrange the stop actuating pedals in a manner to reduce the number of pedals necessary for actuation by the front of the foot, the heel being utilized for actuating one of the pedals.

Other features and objects of the invention will be more fully described in connection with the accompanying drawings and will be more particularly pointed out in and by the appended claims.

In the drawings:—

Fig. 1, is a view in side elevation of one form of the device of my invention showing a banjo mounted in position and looking from the players side of the device.

Fig. 2, is a sectional view on line 2—2 of Fig. 1, looking from the right of the latter.

Fig. 3, is a plan sectional view on line 3—3 of Fig. 1.

Fig. 4, is an enlarged sectional view on line 4—4 of Fig. 2, looking toward the right of said figure and showing the position of the strings and frets with respect to the string stops.

Fig. 5, is an enlarged fragmentary view looking from the right of Fig. 2, toward the string picking mechanism and viewing the parchment side of the banjo.

Fig. 6, is a sectional view on line 6—6 of Fig. 7, looking toward the left of the latter, and showing the initial or normal position of all the pickers with respect to the strings.

Fig. 7, is a sectional view on line 7—7 of Fig. 6, looking toward the right of the latter and showing only the first picker means.

Fig. 8, is a view similar to Fig. 7, showing the picker partly depressed and placing a string under tension.

Fig. 9, is a similar view after the picker has released the string and illustrating how the picker is retracted to permit free sounding vibration of the picked string.

Fig. 10, is a sectional view on line 10—10 of Fig. 1.

Fig. 11, is a sectional detail on line 11—11 of Fig. 4.

Like characters of reference designate similar parts throughout the different figures of the drawings.

As shown, the frame consists of transversely disposed feet 1 and 2 on which are rigidly mounted combined longitudinally disposed guide and frame members 3 and 4. Upright

frame members 5 and 6, secured to the feet 1 and 2, and to guide members 3 and 4, serve as a support for an instrument and also picking and stopping means operating on the instrument. In addition, said upright members 5 and 6 support and are suitably secured to sets of upper and lower guide members 7 and 8 and 9 and 10, respectively. The members 7 and 9, are connected by a brace 11, and by a brace 12, so that the instrument can be inserted into position endwise between the members 7 to 10, as shown. In the case of a banjo, as shown, the upright 6 is equipped with abutment blocks 13 and 14, against which the cylindrical sounding body 15, of the banjo abuts. The neck 16, of the instrument extends toward the upright 5, and the head terminal of the neck, as shown at 17, fits a recessed block 18', mounted on upright 5. A presser foot 18, engages the back of the neck 16, at 19, and is actuated by a threaded rod 20, having a cranked end 21, and having threaded connection with brace 11. By means of this presser foot, the rim of the banjo is forced into tight engagement with abutment blocks 13 and 14, laterally of the frame. I provide means for snugly holding the instrument in snug engagement with the shoulered portions of abutments 13 and 14 and forcing the head end 17, firmly into block 18', which means I will next describe.

A block 22, on brace 11, which is really a fulcrum block, is suitably recessed to receive a short thrust bar 23, or rather, one end thereof. The other end extends into and against the inside face of the sound box 15. Between the ends of this bar is a bolt 25, secured to brace 11, and on which is a nut 26, which, when turned home, tightly impinges the entire instrument against its heretofore described abutments and firmly holds the instrument in a fixed position.

It will be clear that it would be a mere matter of mechanical skill to vary the position and proportions of the aforesigned anchorage means to accommodate stringed instruments of a slightly different form and size from the banjo shown.

The head 26' is shown provided with string tightening devices generally indicated at 27, strings 28, 29, 30 and 31, connected with a usual tail piece 32 and extending over a bridge 33, interposed between the tightened strings and the parchment 34, along the front 55 of the neck 16 to the tightening devices 27. The face of the neck 16, may or may not have frets 35, as diagrammatically indicated in Fig. 4.

I will next describe my improved pedal operated mechanism for stopping the strings 28 to 31, at various points along the face of the neck 16, and in different combinations to obtain different chords.

My improved pedal operated stopping mechanism is in the form of a unitary frame

structure which slidably coats with guides 3 and 4, on which the structure is supported, and which also coats with guides 7 to 10. The lower portion of said mechanism consists of transverse members 36 and 37 which, as seen in Fig. 2, span and ride upon guides 3 and 4. These transverse members 36 and 37 are connected with longitudinal members, one of which is shown at 38, to form a rigid base. The members 36 and 37 are provided with guide feet 39, secured at 40, to member 36, only one set of guide feet being shown. These guide feet suitably coat with guides 3 and 4, as clearly shown in Fig. 2, to hold the base of said mechanism in secure sliding connection with guides 3 and 4. In Fig. 3, I have shown a longitudinal strip 41, which is adapted to have sliding engagement with guide 4, and which is secured to members 36 and 37. A like strip 42, likewise secured to members 36 and 37, slidably engages guide 3, and forms a hinge mounting bar, as will be presently described.

I will hereinafter refer to the foregoing as the sliding base frame of the stopping mechanism.

Stop pedals 43, 44 and 45, are secured to said base frame by hinges 46, 47 and 48, which are connected with strip 42, as clearly shown in Fig. 3. To these pedals are anchored, in any suitable way, the lower ends of operating cables 49, 50 and 51. These pedals are provided with toe treads 52, 53 and 54, upon which the front portions of the shoe of the operator are adapted to be imposed. A feature of novelty of these treads, apart from the same as such, consists in making the tread 53, of the middle pedal 44, sufficiently lower than the treads of the outside pedals in order that the foot of the operator may be shifted from one tread to the other without accidentally depressing the wrong pedal. In case all the treads were of the same height, the margin on the sole of the shoe might cause one outside pedal to be depressed when it was desired only to depress the middle pedal of the bank. This will be clear when it is considered that these pedals are spaced as closely toward each other as possible to thereby limit, as far as may be, the extent to which the foot must be shifted from one pedal to the other. This bank of stop actuating pedals also includes a heel pedal 55 which is connected with the lower end of a stop actuating cable 56, at one end of pedal 55, the remaining end being hingedly connected at 57, with strip 36. This pedal 55, is provided with heel blocks 58 (Fig. 3), between which the heel of the shoe of the player is disposed and at all times engaged so that irrespective of the depression of any one of pedals 43 to 45, the pedal 55, can be depressed or released. Thus the left foot of the player may be shifted about A, as a center, into engagement with the treads of either of the

other pedals, as indicated by dotted lines B, C and D, in Fig. 3.

The stopping mechanism includes an upright frame supported on the base frame and said upright frame consists of uprights 59, 60, 61 and 62. This upright frame supports the stopping mechanism, proper, adjacent the neck of the instrument and in sliding relation to guides 7 to 10. Viewing Fig. 1, the guides 10 7 to 10 are secured at their left hand ends to upright 5 and are held in proper spaced relation thereby as will also be clear by reference to Fig. 2. At their right hand ends, said guides 8 and 10, are suitably secured to upright 6 while guide 9, is supported by brace 63, having its lower end 64, secured to upright 6, and its upper end 65, secured to guide 9. A brace 12, heretofore described, connects guides 7 and 9, so that the instrument can 20 be freely inserted between the guides 7 to 10 from the right hand ends thereof, viewing Fig. 1.

The actual stopping mechanism, is carried by a stopping frame which will next be described.

This frame includes bars 66, 67, 68 and 69 which are disposed abreast of guides 7 to 10, as clearly shown in Fig. 2. The bars 66 to 69 are secured in the disposition shown, by 30 metal strips 70, 71, 72 and 73, which are vertically disposed and which have terminal ends slidably engaging the lateral faces of bars 66 to 69. Strips 74 to 77, are horizontally disposed and are suitably secured to bars 66 to 69 and engage the lower faces of bars 7 and 8, and the upper faces of bars 9 and 10. In practice the arrangement is such that friction due to sliding engagement of these parts is reduced to a minimum, the major friction 40 being upon the guides 3 and 4, which are the supporting guides, near which foot thrust is imposed to shift the stopping mechanism to various positions relative to the strings, as will hereinafter be described.

I will next refer to that portion of the stopping mechanism which actually engages the strings, and to the means and manner in which the same is actuated.

Stopper rods 78 and 79 are longitudinally 50 slidable in bars 67 and 68 and are polygonal so as to be non-rotatively mounted whereby the stops carried thereby will be held in a predetermined position with respect to the strings. Rod 79, has an arm 80 on which a stop 81 is mounted, the string engaging portion 82, being of a suitably soft material. This stop is an elongated stop which is proportioned to engage all of the strings 28 to 31, when actuated. A coiled or like spring 55 83, normally acts to withdraw stop 81, away from engagement with the strings. Operating cable 56, having its lower end connected with heel pedal 55, is trained over pulley 85, loose on spindle 86, and over pulley 87, loose 60 on spindle 88, from which it extends toward

and is connected with rod 79. Thus, when heel pedal 55, is depressed, all the strings will be engaged by stop 81. Rod 78, has an arm 89, which carries stop 90, the latter being adapted to engage string 28. Rod 68 is slidably and non-rotatively mounted in bars 67 and 68 and is normally retracted away from string 28 by spring 90'. Cable 51 is trained about pulleys 91, 92 and 93, loose on spindles 94, 86 and 88 and is connected with rod 78, 75 to draw stop 90 against string 28.

Rod 95, is slidably and non-rotatively mounted in bars 66 and 69, and carries an arm 96, on which are fixed stops 97, 98 and 99, arranged to engage strings 31, and 29, the last 80 numbered stops both engaging string 29 on different sides of a fret. Spring 100, normally retracts said rod and its stops and the cable 49 is connected with rod 95 to actuate the same. Said cable 49 is trained over pulleys 85 101 and 102.

Rod 103, longitudinally slidable and non-rotatively mounted in bars 66 and 69, has an arm 104 that carries stops 105 and 106, adapted to engage strings 31 and 30, respectively, 90 on opposite sides of a fret, as will be clearly seen in Fig. 4. A spring 107 normally acts to retract said rod and its stops. The cable 50, is connected with said rod 103, and is trained over pulleys 108 and 109. The spindles 88 95 and 86, are mounted on strips 70 and 71, and the spindle 94 is mounted on uprights 61 and 62, as clearly shown in Fig. 2.

I will next refer to my improved picker mechanism by referring first to the pedal 100 means whereby the same is operated.

Pedals 112, 113 and 114 are hingedly connected at 115, 116 and 117, respectively, to an elevated strip 118', mounted on guide 3. Said 105 pedals have toe treads 118, 119 and 120, respectively, the central tread 119, being somewhat less in height than the others, for the same reasons heretofore pointed out in connection with the toe treads of pedals 43 to 45. A heel block 121 is centrally recessed at 122, and has laterally disposed projections 123 to hold the heel of the player's shoe in a substantially central position as the toe is shifted from one tread to the other. Picker operating cables 124, 125 and 126, have their lower 110 ends secured to pedals 112, 113 and 114, respectively, and extend upwardly therefrom for a purpose which will next be described. It will be clear that the picker operating 115 pedals are not shiftable laterally of the frame, as is the case with the stop operating 120 pedals.

I will next refer to the picker mechanism, proper, and the reader's attention is directed more particularly to Figs. 5 to 9.

What I will term a picker guide board 127, is suitably secured to the frame of the machine and extends vertically abreast of the parchment side of the instrument transversely of the strings and at one side of the bridge 130

33. Said board 127 has a spring suspending ledge 128 from which springs 129, 130 and 131, are suspended. I have shown three picker blocks 132, 133 and 134, the first acting 5 on string 29, the second acting on strings 30 and 31, and the third acting on string 28. Although each block will be separately designated by reference numbers, only one need be described in detail as all are the same in 10 structure and function except that block 133, picks two strings instead of one, which I consider a novel feature, and which I will later describe in detail.

Block 132 has a picker end 135 provided 15 with a picker 136 which latter consists of a tapering elongated projection from the body of the block and which is adapted to engage a string and tension it, and then suddenly release the tensioned string to permit the latter to freely exercise or impart a tonal vibration, through the bridge 33, and parchment 34. Said block also has an actuated or cam end 137, which is offset downwardly from the picker end 135, as clearly shown in Fig. 7. 20 This offset results, as far as the upper edge is concerned, in the formation of a guiding edge 138, which is adapted to coact with edge 139, of an opening 140, in board 127, through which, and in which the picker block is 25 floatingly shifted from one position to another. On the back of board 127, is a cam block 141, with which a resilient cam rod 142, coacts. This cam rod 142 is rigidly mounted in the cam end of picker block or head 132, and has 30 a straight section, as indicated by said numeral, an inclined section 143 and a board section 144. Projecting from opposite sides of the picker head 132, are cam shifting studs 145 which normally engage the rear side of 35 board 127, as in Fig. 7, to prevent the picker head from approaching the parchment 34, to a too great extent. On the back of board 127 is secured a forked cam having its lower portion 146 fixed to said board by means such as 40 screws 147. The forked ends 148, of said cam extend on opposite sides of the cam end of the picker head 132 and are recessed to form releasing shoulders 149. As will be seen from 45 Fig. 5, the studs 145 are sufficiently short to 50 pass through cam 146 when said studs descend below said shoulders 149. It will be noted from Fig. 7, that the forked ends 148 are curved outwardly from the rear face of board 127 so that the actual forked ends are 55 substantially parallel with said board along their operatively effective length. The floating picker head 132 is actuated by a yoke having a bight 150 with which the upper end of cable 126 is connected, as shown in Fig. 7. 60 Thus picker head 132 will be actuated when pedal 114 is depressed. Guide strips 151 and 152 have suitable openings through which limbs 153 and 154 of the yoke slidably extend, the upper end of limb 153 being pivotally 65 connected at 155 and the limb 154 being pivotally

connected at 156, with the picker head, the two points of pivotal connection being near the ends of said head. Said yoke will be made of sufficiently bendable wire or the like to freely permit said head 132 to partake of such shifting and floating movements as its controlling auxiliaries will permit, or afford. 70

I will next describe the operation of the picker head with reference to Figs. 7, 8 and 9. 75

First, it will be noted that the disposition of spring 129, is such that the picker head 132 is normally advanced toward the string 29, when said head is in the position shown in Fig. 7. Now as the pedal 114 is depressed, the head 132 will next assume the position shown in Fig. 8, exerting a maximum tension on string 29. As said head 132 approaches this position, the studs 145 will have descended below the tops of cams 148 and will be disposed against the inside faces of the latter, as a result of the shifting or deflecting section 143, riding outwardly on cam block 141. Edge 138, riding on the top 139, of slot 140, steadies the picker head in its outward movement. Now it will be clear that the string 29, is not only drawn downwardly, but also outwardly to the right of Fig. 7, while being tensioned by picker head 132, and this slight outward movement of the head precedes the quick release of the string, which is a special feature of novelty of my invention. In other words, it is because of this outward movement of the head that I am able to obtain such an overlap-engagement 95 of the picker end 136, initially. Thus, there is, in addition to a "pull", a certain "drag" on the tensioned string, so that when it is released, its resulting sounding vibration is all the more effective, in addition to closely 100 simulating the natural pick of the human hand. Further, this "draw-away" action of the picker 132, preceding release of the tensioned string, more positively assures a complete release of the tensioned string with the 105 picker far enough away from the string so that the latter cannot be interfered with or damped by contact with the picker during subsequent vibration of the released string. 110

As head 132, is depressed slightly further than shown in Fig. 8, section 143 will gradually shift head 132 to the right until string 29 is actually released, which condition is just ready to occur, in the position shown in Fig. 8. It will be noted that in the Fig. 8 position, studs 145 are in contact with cams 148 and that as studs 145 descend against said cams 148 they force the latter to the right, said cams 148 being resilient for this purpose. Thus, when studs 145 reach a position sufficiently below shoulders 149, the studs 145 will suddenly be released and will move slightly further to the right when so released, while the tensioned cams 148 will suddenly 125 flip to the left, thereby insuring a disposition 130

of the studs on the right hand or outer faces of cams 148, on the return or upward movement of studs 145, as shown in Fig. 9. The player will, as he becomes skilled in playing 5 the instrument, release the pedal just as soon as he hears the picked string sound. During this return movement, the studs will ride up on the outside or right hand faces of cams 148, under the pull of spring 129. The cam 10 rod 142, will hold the picker head in a retracted position until after section 143 has reached the position where section 144 is in contact with the board 127. Just prior to this position of the parts, the studs 145 will 15 have reached the tops of cams 148 and at the moment that the studs 145 are freed from the cams 148, the forward pull of spring 129 will serve to quickly return the picker 132 to the position shown in Fig. 7. The cam edge 138, 20 coacting with edge 139, serves to guide the picker head back to normal.

Thus, it will be seen that I obtain a quick return of the picker head to a normal position, as shown in Fig. 7, and I consider this 25 a very important feature of my invention, especially in playing chords rapidly.

Picker head 134, which operates string 28, is in all respects the same in structure and operation as head 132, and is connected to 30 cable 124.

Picker 133, is the same as its companion pickers except that it acts upon strings 30 and 31, and hence, the corresponding cams 157 are longer than cams 148, and the slot 158, is 35 correspondingly lengthened. Further, this picker head 133, does not partake of any withdrawing action away from the strings until after it has acted upon the last or lowest string 31, whereupon, its withdrawal action 40 is the same as heretofore explained in connection with picker 132. Likewise, its quick return is the same.

It will thus be seen that I have shown 45 picker means acting singly and plurally on the strings to tonally vibrate the latter.

In order to guide the player in shifting the string stopping mechanism to the right positions in order to dispose the stops in proper relation to the frets, I have shown the guide 50 3, graduated, as will be clearly seen by reference to Fig. 3. In the event that the instrument being played has no frets, the skill of the player will be relied upon to shift the stopping mechanism to the right position.

55 As the mechanical operation of the stops will be clear from the foregoing description, it need only be stated that the stop 81, engages all the strings simultaneously, and when applied at different points along the neck face, the musical key of all the strings will be correspondingly changed, dependent upon the position of said stop 81. This corresponds with manual playing where the fore or index finger is applied to stop all the 60 strings. The remaining stops change the key

of the chords picked, the same as though the human fingers were applied, the key being changed in accordance with the longitudinal position along the strings where the stops are applied.

This is primarily a chord player and is not intended primarily to play an air or melody, as the stops are not capable of as much flexibility and variation of operation as the fingers of the human hand. However, the device is equal to the human hand as a chord player, and the device of my invention is primarily designed for supporting work, not so much for solo work. Thus, a performer can utilize this device, operating the same with 70 his feet, to play supporting chords, in support of a solo instrument played by his hands.

I will next describe my improved sound 75 dampener.

Referring to Figs. 1 and 10, 160 designates 80 the usual body bar, fixed in the body 15. Pivoted at 161, on said bar is a forked dampener 162, which straddles the bar 160, the forked ends 163 being adapted for engagement with the parchment 34, preferably at the right of 85 the bridge 33, with respect to Fig. 1. Said dampener has an operating end 164 which is connected by a link 165 to the upper end of a knee operated lever 166, which is pivoted at 90 166', to a part of the frame. Said knee lever 95 has a projection 167, on its lower end that may be engaged by the knee of the right leg of the operator and shifted in the direction of the arrow shown in Fig. 1, to cause the dampener to engage the parchment and 100 dampen the sound. A spring 168, serves normally to maintain the dampener free from engagement with the parchment.

It is believed that my invention will be 105 fully understood from the foregoing description and while I have herein shown and described one embodiment of my invention, I do not wish to be limited thereto except for such limitations as the claims may import.

I claim:—

1. In a means for playing a stringed instrument having a sounding body and a neck, a frame for holding the instrument, pedal operated mechanism on said frame for plucking the strings abreast of the sounding body, 115 and pedal operated mechanism for pressing and stopping the strings along the neck of the instrument, said last named mechanism being slidably mounted on said frame for movement to different positions along the instrument's neck.

2. In a stringed instrument player, a floating picker head normally in a picking position, pedal means imparting movement of said head throughout a picking stroke, means gradually withdrawing and then quickly releasing said head from the string during such picking stroke, means imparting a return stroke to said head, and means acting during such return stroke to quickly release said 120 125 130

- head for movement into a picking position.
3. In a stringed instrument player, a picker guide board having a slot therein, a picker head floatingly slidable in said slot into and out of picking positions, means for actuating said head to pick a string, means for restoring said head to a normal position, and instrumentalities acting on said head to quickly withdraw the latter from a picked string and retain said head free therefrom and finally restoring said head to a normal position.
4. In a stringed instrument player, a picker board having a slot therein and a cam block adjacent said slot, a picker head floatingly slidable in said slot, means for moving said picker head throughout a picking cycle, and said head having a cam rod engaging said block to withdraw said head from engagement with the string during the picking stroke of said head.
5. In a stringed instrument player, a picker board having a slot, a picker head floatingly slidable in said slot throughout its picking and return movements, said head having studs engaging said board to limit movement of said head toward the string to be picked, a forked retaining cam spanning said head, and means for retracting said head on the picking stroke thereof and disposing said studs in tracking engagement with said forked cam on the return stroke of said head to hold said head away from the string until said head reaches a predetermined position with respect to said string, and means freeing said studs from said forked cam and advancing said head into a picking position with respect to the string.
6. In a picking means for a stringed instrument player, a picker board having a slot therein, a picker head floatingly slidable in said slot and having a picker end projecting from the string side of said board and a cam end projecting from the cam side of said board, means for imparting picking movement to said head including a yoke having one limb thereof pivoted to the picker end of said head and another limb pivoted to the cam end of said head for moving said head substantially transversely to its length, and instrumentalities for imparting movement of said head substantially in the direc-
- tion of the length of the latter during actuation of said head by said means.
7. In a picking means for a stringed instrument player, a picker head, means moving said head into picking relation with a plurality of strings, means holding said head to a string picking path during picking actuation of said head, means for restoring said head to a starting position, and means for maintaining said head free from said strings during restoring movement of said head.
8. In a stringed instrument player, a floating picker head, means for actuating said head to pick a plurality of strings, and mechanism for controlling said head during picking movement thereof.
9. In a stringed instrument player, a floating picker head, means for actuating said head to pick a plurality of strings, means for returning said head to a normal position, and mechanism for controlling said head during its picking and return movements.
10. In a stringed instrument player, stopping mechanism adjustable to different longitudinal positions along the neck of the instrument and provided with reciprocable stop rods having stops, and means carried by said mechanism for selectively actuating said rods to engage the stops thereof against the strings of the instrument.
11. In a stringed instrument player, a frame for holding the body and neck of the instrument, stop mechanism including a stop arm extending across and longitudinally abreast of a plurality of strings of the instrument, and said arm having a plurality of stops for simultaneously engaging a plurality of different strings at different longitudinal positions therealong.
12. In a stringed instrument player, a frame for holding the body and neck of the instrument, stop mechanism including stops for engagement with one or more strings along the neck of the instrument, toe actuated pedals for operating said stops, an elongated stop for engagement with all the strings to change the playing key, and a heel operated lever for actuating said elongated stop.

In testimony that I claim the foregoing as my own, I hereby affix my signature.

JOEL B. WOLFE.
